DESIGN FOR AN ELECTRIC REMOTE CONTROL CASING OR THE LIKE

Paul M. Fuller, Chicago, Ill., assignor to The
Rudolph Wurlitzer Company, a corporation of
Ohio

Application May 10, 1939, Serial No. 84,904

Term of patent 7 years

To all whom it may concern:

Be it known that I, Paul M. Fuller, a citizen of the United States, residing at Chicago, in the county of Cook and State of Illinois, have invented a new, original, and ornamental Design for an Electric Remote Control Casing or the like, of which the following is a specification, reference being had to the accompanying drawing, forming a part thereof.

Figure 1 is a perspective view of the electric

remote control casing or the like embodying my design. Figure 2 is a side elevation thereof. Figure 3 is a top plan view of the same. That side of the casing not shown in the drawing is the same as the side shown.

I claim:

The ornamental design for an electric remote control casing or the like, substantially as shown and described.

PAUL M. FULLER.
